UNITED STATES PATENT OFFICE.

ALBERT LATHAM, OF BEVERLY, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

SKIVING-MACHINE.

1,266,027.

Specification of Letters Patent. Patented May 14, 1918.

Application filed August 13, 1915. Serial No. 45,402.

To all whom it may concern:

Be it known that I, ALBERT LATHAM, a citizen of the United States, residing at Beverly, in the county of Essex and State 5 of Massachusetts, have invented certain new and useful Improvements in Skiving-Machines; and I do hereby declare the following to be a full, clear, and exact description of the invention, such as will enable 10 others skilled in the art to which it appertains to make and use the same.

The present invention relates to skiving machines and more particularly to machines of this character which comprise a rotary 15 skiving knife and coöperating gage and presser members for guiding and feeding the work to the knife.

One object of the present invention is to provide mechanism operating in an im- 20 proved manner for producing a true cutting edge which may be embodied in existing machines without materially changing or modifying the machines.

A further object of the invention is to 25 provide a simple and compact grinding mechanism operating in an efficient manner to form the cutting edge upon a rotary skiving knife.

With the above objects in view the se- 30 veral features of the invention consist in cer- tain novel features of construction, combi- nations and arrangements of parts herein- after described and claimed, the advantages of which will be obvious to those skilled in 35 the art from the following description.

In the accompanying drawings illustrating the preferred form of the invention; Figure 1 represents an end elevation of a skiving machine showing the application of 40 the improved grinding mechanism thereto; Fig. 2 is a detail showing a section in plan of the grinding mechanism and the portion of the skiving knife upon which it operates; Fig. 3 is a section upon the line 3—3 45 of Fig. 2, illustrating the mechanism for adjusting the grinding disk relative to the knife; Fig. 4 is a view showing in an ap- proximate manner and upon a greatly en- larged scale the lines which are formed upon 50 the surface of the knife by the action of the grinding disk; and Figs. 5 and 6 are views partially diagrammatic, illustrating the manner in which the face of the grinding

disk engages with the inner surface of the skiving knife.

In the skiving machines of this type comprising a tubular skiving knife it has been found desirable to grind the knife upon both surfaces in order to produce a cutting edge which conforms to the true circle of 55 rotation of the knife. In the preferred form of the invention a bevel cutting face is formed upon the outer surface of the knife to put the cutting edge at the opposite surface, and the inner surface of the knife is 60 ground sufficiently to true it up and remove any eccentricities which may be present. In existing machines of this type which are employed to a considerable extent it is cus- 65 tomary to grind only the outer surface of 70 the knife to form a cutting edge without grinding the inner surface of the knife to remove inequalities in the surface. In order to adapt existing machines for grinding both the inner and outer surfaces of the 75 knife to form a true cutting edge, the pres- 80 ent invention contemplates the provision of mechanism which may be permanently em- bodied in existing machines without sub- 85 stantially changing or modifying the ma- chine, and which may be operated whenever 90 desired to true up the edge of the knife.

In the illustrated embodiment of the in- 95 vention a skiving machine is shown of the general type disclosed in the patent to Alex- 85 ander No. 1,117,541, granted November 17, 1914, and comprising a tubular skiving knife indicated at 1, rotating in a casing 3 and having a presser foot or gage member 4 supported in an overhanging arm 5. The 90 casing is provided with a hinged portion 6 which carries the coöperating feed roll and actuating mechanism and which, as shown in Fig. 1, may be conveniently opened and turned back to permit access to the in- 95 terior of the knife. The tubular skiving knife 1 conveniently comprises a knife blade 7 which is supported upon an adjust- 100 able blade carrier 8 and is clamped in a substantially cylindrical holder 10 by clamp- 105 ing segments 11. A bevel cutting face is formed upon the outer surface of the knife by a grinding disk 13 journaled in a sup- porting bracket 15 which may be moved to carry the periphery of the disk into and out of engagement with the surface of the

knife, all as shown and described clearly in the application above referred to.

The inner surface of the knife is engaged by a grinding disk 20 journaled in a head 21 which is adjustably supported in a bracket 22 secured to the casing 3 of the machine. The bracket 22 is conveniently secured to the casing 3 by a bolt 24 and is positioned properly by projecting pins 25 which engage with co-operating recesses 26 formed in the casing. The disk supporting head 21 is provided with an arm 28 which is received in the sleeved portion of the bracket, as shown clearly in Figs. 2 and 3 and is clamped in position by a transverse clamping bolt 29 which tends to draw the two split portions of the sleeve together. In the present invention the grinding disk is supported with its face in operative relation to the surface of the knife and the engagement of the face of the disk with the surface of the rotating knife causes a rotation of the disk about an axis substantially at right angles to the axis of the knife. In the illustrated embodiment of the invention the face of the disk engages with the surface of the knife at one side of the axis of the disk and the relative rotation of the knife and disk causes the grinding of the inner surface of the knife in a series of lines which cross one another, as shown in Fig. 4, to form a finely serrated cutting edge. It will be obvious to those skilled in the art that the working face of the disk forms a chord intersecting the curved surface of the knife at two points, the length of the chord depending upon the degree of curvature of the knife surface and upon the location of the disk relative to the knife. This construction and mode of operation serves to grind the surface of the knife in an extremely efficient manner and with a simple mechanism and at the same time produces a highly efficient form of cutting edge. The grinding disk preferably consists of a grinding ring 30 which is secured to a metal supporting plate 31 which is held upon the end of a spindle 32 by a clamping bolt 33, as shown clearly in Fig. 2, to present the face of the grinding ring in operative relation to the inner surface of the knife. The spindle 32 is slidably supported in the head 21 substantially at right angles to the axis of the knife and is normally moved in a direction to cause the engagement of the grinding disk with the knife by a spring 35 received in a bore 36 formed in the head 21 and interposed between the head and a thrust collar 37 secured to the spindle. It will be obvious that as the grinding disk is rotated by the frictional engagement of the face of the disk with the surface of the knife the spindle 32 must be free to rotate in the head 21 and to this end the spring 35 engages with a plate 38 which is supported by an anti-

friction thrust bearing 39 interposed between the plate and the thrust collar 37. The movement of the grinding disk toward the surface of the knife is limited and the operative position of the grinding disk is accurately determined by an adjustable plug 40 threadedly received in the head 21 and having its inner end engaging with the thrust collar 37, as shown clearly in Fig. 2, to determine the position of the spindle 32. With this construction the movement of the grinding disk in the direction of the surface of the knife is positively limited and mechanism is provided for yieldingly maintaining the grinding disk in this operative position. The grinding disk may be conveniently manipulated to remove it from engagement with the surface of the knife, or to prevent the rotation when in contact with the surface of the knife by a knurled handle 41 secured to the outer end of the spindle. The head 21 is supported upon the outside of the casing 3 and projects through a slot 43 formed in the casing to support the grinding disk adjacent the inner surface of the knife, and it will be noted with this construction that only slight changes are necessary in the casing 3 to attach the present grinding mechanism to existing machines. It is preferable to slightly incline the axis of the grinding disk with respect to the normal, thus bringing the two portions of the face of the disk engaging with the surface of the knife into closer proximity to one another and to this end, as shown clearly in Fig. 2, the grinding disk is supported with its axis inclined slightly to the plane of rotation of the skiving knife.

In order to move the grinding disk in a rectilinear path in the direction of the knife axis, an adjusting plug 44 is threadedly received in the end of the bracket 22 and bears against the end of the arm 28, as shown clearly in Fig. 2. In order to retain the arm 28 in the bracket without turning, the arm is provided with longitudinal grooves or recesses 45 which are engaged by positioning screws 46 threaded in the bracket 22, as shown clearly in Fig. 3. By relatively adjusting the two screws 46 the arm may be slightly turned in the bracket 22, adjusting the grinding ring angularly in the plane of the knife edge.

The term "face" when applied to that portion of the grinding disk which operatively engages with the surface of the knife throughout the present specification and claims is considered as the substantially flat face of the grinding ring, as distinguished from the peripheral surface of the ring.

While it is preferred to employ the specific construction and arrangement of parts shown and described, it will be understood that this construction and arrangement is not essential except so far as specified in

the claims, and may be changed or modified without departing from the broader features of the invention.

The invention having been described, 5 what is claimed is:

1. A skiving machine comprising a tubular skiving knife, a grinding disk engaging with one surface of the knife to form a bevel cutting face, and a grinding disk supported 10 in operative relation to the opposite surface of the knife with the face of the disk arranged to contact with the moving surface of the knife.
2. A skiving machine comprising a tubular skiving knife, and a grinding disk supported in operative relation to the inner surface of the knife with a face of the disk contacting with the knife surface so that the face of the disk moves across the path of 15 movement of the knife surface when the disk is rotated.
3. A skiving machine comprising a tubular skiving knife, a casing, a bracket secured to the outside of the casing, a spindle supported in the bracket and projecting within 20 the casing, a grinding disk mounted upon the inner end of the spindle and arranged with one face in operative relation to the inner surface of the knife, and means for 25 moving the grinding disk into contact with the knife.
4. A skiving machine comprising a tubular skiving knife, a grinding disk positioned in operative relation to one surface of the 30 knife, and means for supporting the disk with its face in operative relation to the surface of the knife, constructed and arranged to cause the knife surface to be ground by the face of the disk in a series of 35 intersecting lines to form a serrated cutting edge.
5. A skiving machine comprising a tubular skiving knife, a grinding disk, a spindle supporting the disk with one face in opera- 40
6. A skiving machine comprising a skiving knife, a stationary bracket, a spindle slidingly supported in the bracket, a grinding disk mounted upon the end of the spindle in operative relation to the knife, a 45 spring for normally moving the disk into contact with the knife, and an adjustable stop for limiting the movement of the disk toward the knife. 50
7. A skiving machine comprising a skiving knife, a casing, a bracket secured to the outside of the casing and adjustable axially of the knife, a spindle slidingly supported in the bracket and projecting within the casing, a grinding disk mounted on the inner end of the spindle and arranged to engage 55 with the inner surface of the knife, and means for limiting the movement of the spindle in the direction of its length toward the knife. 60
8. A skiving machine comprising a skiving knife, a bracket having a recess formed therein, a spindle slidingly mounted in the bracket, a grinding disk secured to the spindle, a spring located in the recess and normally tending to move the grinding disk 65 into contact with the knife, and a stop adjustably secured in the bracket to limit the movement of the disk toward the surface of the knife. 70
9. A skiving machine comprising a tubular skiving knife, a grinding disk having one face arranged in operative relation to the inner surface of the knife, means for supporting the grinding disk with its axis of rotation inclined to the plane of the knife 75 edge, and means for moving the disk toward the surface of the knife. 80

ALBERT LATHAM.
